UNITED STATES PATENT OFFICE.

JOHN H. GEORGE, OF BRIDGEPORT, CONNECTICUT, ASSIGNOR TO ELLSWORTH A. HAWTHORNE, OF BRIDGEPORT, CONNECTICUT.

ELECTRIC LIGHTING APPARATUS.

1,393,357.

Specification of Letters Patent. Patented Oct. 11, 1921.

Original application filed March 16, 1918, Serial No. 222,975. Divided and this application filed November 23, 1918. Serial No. 263,904.

To all whom it may concern:

Be it known that I, JOHN H. GEORGE, a subject of the King of Great Britain, and a resident of Bridgeport, in the county of 5 Fairfield and State of Connecticut, have invented an Improvement in Electric Lighting Apparatus, of which the following description, in connection with the accompanying drawings, is a specification, like characters on the drawings representing like parts.

This invention relates to electric lighting apparatus, and is more particularly concerned with an electric switch socket and lamp-focusing device having special application to lamps of the class in which an electric bulb is associated with a light-concentrating and projecting reflector. This application is a division of my pending application, Serial No. 222,975, filed March 16, 20 1918.

My invention will be best understood by reference to the following description, when taken in connection with the accompanying drawings of one specific embodiment thereof, while its scope will be more particularly pointed out in the appended claims.

In the drawings:

Figure 1 is a side elevation of an electric lighting apparatus embodying my invention;

Fig. 2 is a sectional view on line 2—2 of Fig. 1;

Fig. 3 is a sectional view of the lamp socket and switch on an enlarged scale;

Fig. 4 is a sectional view on line 4—4 of Fig. 3, showing the switch in full lines in its "off" position, and in dotted lines in its "on" position;

Fig. 5 is a sectional view on line 5—5 of Fig. 3; and

Fig. 6 is a sectional view on an enlarged scale on line 6—6 of Fig. 2, the casing being omitted so as to show, in elevation, the remote end of the switch insulating member.

Referring to the drawings, and to the embodiment of my invention which is illustrated therein, I have shown an electric lighting apparatus comprising a casing 10, best shown in Fig. 2, which may be of any appropriate construction, the same inclosing a suitable light-concentrating and projecting reflector 11, with which is associated a light source 12, herein in the form of an incandescent electric bulb mounted in an ap-

propriate lamp socket 13. Electric bulbs of this class are of two types, one adapted for what is known as a single wire system, and the other for what is known as a double wire system. In the case of the single wire system, the lamp is provided with a single, centrally located terminal at the rear or inner end of its base, and there is provided, associated with the socket, a single yielding terminal contacting therewith; while in the case of the double wire system, the end of the lamp base is provided with two terminals, respectively, adapted for co-operation with two spring-pressed terminals associated with the lamp socket. In the present example, I have shown the two-wire type, and have provided a pair of usual spring-pressed plungers 14 and 15, best shown in Fig. 3, mounted respectively in guide sleeves 16 and 17, and having springs 18 and 19 which urge said plungers into engagement with the lamp base. The sleeves 16 and 17 are herein mounted in an insulating bushing 20 which enters the socket 13 from the rear or inner end thereof.

Associated with the lamp socket 13 are suitable lamp focusing and switching means, which serve as a carrier for the lamp 12, whereby the latter may be focused with relation to the reflector 11, said reflector to this end being provided with a central opening 21 to receive the lamp socket 13, which is slidable axially therein, as best shown in Fig. 2. The switch may take various forms, but in the present example, I have shown a switch comprising a circuit making and breaking lever 22, best shown in Fig. 4, extending lengthwise of the axis of the lamp socket 13, and adapted to make and break the lamp circuit by to and fro movement. To this end, herein I have provided the lever 22 with a cam 23 having endwise engagement with a spring-pressed plunger 24, the latter being preferably mounted in the plunger-guiding sleeve 17, and being urged by the spring 19 into engagement with said cam. The latter serves as a means to hold the switch lever 22 in an open circuit position, as shown in full lines in Fig. 4, or a closed circuit position, as shown in dotted lines. When the switch is thrown from one position to the other, the face of the cam moves across the end of the spring-pressed plunger, causing the latter to yield inwardly,

and when the lever reaches its other position, the plunger, coöperating with the cam, holds the switch definitely but yieldingly in such position.

- 5 The lever 22, when in the position shown in dotted lines in Fig. 4, is adapted to complete the lamp circuit, and to that end may coöperate with any suitable contact member, herein a yielding contact 25 in the form 10 of a spring, best shown in Fig. 5. This spring is preferably so shaped that when the face of the lever 22 wipes across the terminal portion of the spring, the latter yields and insures a firm contact with the lever.
- 15 Any suitable mounting may be provided for the switch, but in the present example, I have shown an insulating mounting comprising a pair of insulating members 26 and 27, which together form a housing for the 20 switch elements, but so constituted that the latter may be assembled and dismounted with great ease. To this end, I have provided the members 26 and 27 with flanges 28 and 29, best shown in Fig. 3, respectively 25 secured to an insulating socket mounting 30 by bolts 31 and 32, and I have provided a bolt 33 passing through the members 26 and 27, as shown in Fig. 3, and securing the same together as well as providing a pivot 30 for the lever 22. Herein, the member 27 is provided with an elongated shallow chamber 34, best shown in Fig. 3, to receive the lever 22, and is provided with another communicating chamber 35 to receive the cam 23.
- 35 As a means for conducting the current to the switch, I have herein provided two conducting wires 36 and 37, suitably connected to the plunger guide 16 and the spring contact 25, respectively.
- 40 As a means for operating the switch, I have herein shown a switch actuator 38, extending transversely of and appropriately connected to the lever 22 to operate the latter, said actuator to this end being herein 45 provided with a recess 39 having opposed shoulders 40, between which the lever is interposed, as best shown in Fig. 6. Thus, it is evident that by shifting the actuator 38 endwise in the proper direction, the lever 50 may be shifted from one position to another. Preferably the actuator is provided with suitable push buttons 41, one of which is pressed inwardly to complete the circuit, and the other is pressed inwardly to break 55 the circuit. These buttons may be assembled with the switch, after the latter is in place in the casing, by inserting said buttons laterally through the casing. Preferably, said buttons are threaded onto the intermediate portions of the actuator, as 60 shown in Fig. 6.

Herein, the push buttons 41 extend laterally through the casing 10, as best shown in Fig. 2, said casing being provided with appropriate guides 42 to guide said buttons,

while preventing them from being moved lengthwise of the axis of the lamp socket and switch, the latter, however, being mounted to move axially for lamp focusing purposes. The insulating members 26 and 27 are herein provided with longitudinal slots 43 and 44, which permit the switch to be moved to and fro with relation to the switch actuator which, as just stated, is held against movement lengthwise of the axis of the switch, as will be evident from an inspection of Figs. 2 and 3.

It is evident from the foregoing that the switch mounting constitutes a lamp carrier mounted to move axially in the casing. As 80 a means for moving said carrier forward and backward to focus the lamp 12 with relation to the reflector 11, I have herein provided a focusing rod 45, suitably attached to the lamp carrier and extending rearwardly therefrom through the casing 10, as best shown in Figs. 1 and 2. Preferably, the means of attachment of the rod to the lamp carrier is such that the rod may be turned without tending to turn the lamp 90 carrier, and hence without danger of injury to the latter. To this end, I have herein provided the rod 45 with an annular groove 46, and a head 47 interlocked with, but mounted to turn freely in the insulating 95 members 26 and 27, as best shown in Figs. 3 and 4, said members to this end being provided with correspondingly shaped depressions 48 and 49.

The lamp when focused may be held in 100 the desired position by any appropriate means, but in the present example, I have shown for such purpose a clamping bushing 50 (see Fig. 2), threaded into the rear end of the casing 10, and provided with one or 105 more slots 51, which render the same expansible and contractible. A tapered end 52 on the bushing fits a correspondingly tapered seat on the casing 10, as shown in Fig. 2, whereby turning movement of the 110 bushing in the proper direction causes the latter to contract and grip the focusing rod 45 which it encircles. Turning movement in the opposite direction releases said rod, and allows the latter to be moved axially 115 for focusing purposes.

Having thus described one embodiment of my invention, what I claim and desire by Letters Patent to secure is:

1. In a lighting apparatus, the combination of a casing, a concave reflector, a lamp associated therewith, and lamp-focusing and controlling means including a lamp-carrier mounted to move axially in said casing, a lamp-controller projecting laterally through 125 said casing, and means to hold said controller against movement with said carrier axially of said casing.

2. In a lighting apparatus, the combination of a casing, a concave reflector, a lamp 130

- associated therewith, and lamp-focusing and controlling means including a lamp-carrier mounted to move axially in said casing and extending rearwardly therethrough, a lamp-controller projecting through and having movement laterally of said casing, and means to hold said controller against movement with said carrier axially of said casing.
- 10 3. In a lighting apparatus, the combination of a casing, a concave reflector, a lamp associated therewith, and lamp-focusing and controlling means including a lamp-carrier mounted to move axially in said casing, and a lamp-controller projecting laterally through guides in said casing, and held by said guides against movement with said carrier.
4. In a lighting apparatus, the combination of a casing, a concave reflector, an electric lamp associated therewith, a lamp-focusing and controlling means including a lamp and switch carrier mounted to move axially in said casing and provided with a lateral opening, an electric switch carried by said carrier, and a switch actuator projecting laterally from said opening through said casing and held thereby against movement lengthwise of the axis of said reflector and lamp.
- 20 5. In a lighting apparatus, the combination of a casing, a concave reflector, an electric lamp associated therewith, and lamp-focusing and controlling means including a
- 5 lamp and switch carrier mounted to move 35 axially in said casing and provided with a laterally disposed longitudinal slot, an electric switch carried by said carrier, and a switch actuator projecting laterally from said slot through said casing and held thereby against movement lengthwise of the axis 40 of said reflector and lamp,
- 15 6. In a lighting apparatus, the combination of a reflector, a light-source associated therewith, a light-source carrier including a 45 pair of insulating members, energy-conducting means connected through said light-source carrier to said light source, and a light-source focusing member journaled in and interlocked between said light-source 50 carrier members to facilitate axial movements of said focusing member.
- 25 7. In a lighting apparatus, the combination of a casing, a reflector, a lamp associated therewith, a lamp socket and a switch 55 mounting arranged for conjoint movement axially of said casing to focus said lamp, a switch arranged lengthwise of the axis of said lamp socket, a switch actuator having movement laterally of said casing and guides 60 for said switch actuator formed in opposite walls of said casing, said actuator being held by said guides against movement with said mounting.
- 30 In testimony whereof, I have signed my 65 name to this specification.

JOHN H. GEORGE.
